UNITED STATES PATENT OFFICE.

CHARLES C. BLACKMORE, OF DAYTON, OHIO.

AMBULANCE.

1,303,016.

Specification of Letters Patent.

Patented May 6, 1919.

Application filed August 21, 1915. Serial No. 46,730.

To all whom it may concern:

Be it known that I, CHARLES C. BLACKMORE, a citizen of the United States, residing at Dayton, in the county of Montgomery 5 and State of Ohio, have invented a new and useful Ambulance, of which the following is a specification.

One object of my invention is to arrange accommodations for four patients lying on stretchers; or two on stretchers and four seated; or eight seated. Another object is to provide supports for stretchers which can quickly be converted into seats and backs for the seats. Another object is to facilitate and 15 simplify the operation of loading and unloading, and to enable two attendants to do it with the least possible effort on their part and with the minimum of disturbance of the patients; also to permit lodgment or removal of any patient without moving or in any way disturbing the other patients. Another object is to enable a surgeon inside to have easy access to each patient, whether lying or sitting.

The following general description will render the detailed description more easily understood. Openings are arranged at the sides long enough to admit a stretcher sideways. Supports are provided to carry stretchers into and out of the ambulance body and the stretchers rest upon these supports while in the ambulance. Two forms of support are provided, one of them slides in and out, and when out is at such a height 30 that two attendants can place a stretcher upon it without being compelled to assume an awkward or difficult position. When placed upon the support the stretcher is wholly outside of the body. The support 35 with the stretcher on it is slid into or out of the body with but little effort and without jarring the patient. The other support is carried on parallel links and when in the body is above the sliding support, leaving ample space to enable an attendant to work 40 on the patient below. This support rocks on the links outward and downward, the links finally coming to rest on stops, the support then being at the same height as the sliding support. Each support may be moved in or out, with or without a patient, without disturbing the patient on the other support.

The supports are made in the form of trays and the under surfaces are upholstered. 55 The upper support or tray is pivotally attached to a tie bar which connects the upper ends of the links and may be rocked on this pivot and placed in position to act as the back of a seat. The lower tray has folding 60 legs and may be inverted and stood on the legs to form the seat. Two supports are thus convertible into an upholstered seat capable of accommodating four or five persons. The sides of the body are hinged at the top 65 and provided with braces enabling them to be held open to different extents. The lower portions of the sides are flexible so as to be rolled up. The trays are provided with sockets to receive the legs of the stretcher 70 which materially adds to the comfort of the patients.

In the accompanying drawings, which are as nearly diagrammatic as is possible,

Figure 1 is a side elevation of the body 75 of my ambulance, with portions broken away. It is to be understood that my invention is confined to the body and that it is not necessary to show the running gear.

Fig. 2 is a rear elevation with the inclosing portions of the back removed.

Fig. 3 is a similar view showing the trays in position to form a seat.

Fig. 4 shows the end of a lower tray, partly in section, withdrawn from the body 85 and carrying a stretcher.

Fig. 5 shows a portion of a lower tray with a stretcher in place.

Fig. 6 is a plan of a portion of a lower tray and one of the bars which carry it. 90

Similar numerals refer to like parts in all of the views.

Referring to Fig. 1 it is seen that at each end of the floor 25 there is a narrow pocket 26 to receive the lower ends of links 27 and 95 28. Each link 27 is pivoted to the wall of a pocket. Links 28 are secured to the ends of rock shafts 29 (see Fig. 1), whereby they are compelled to move in unison. The upper end of each link 27 is connected to the 100 upper end of a link 28 by a tie-bar 30, and the trays are pivotally attached to these tie-bars at 31. The tie bars normally hold the trays level as in Fig. 2, where the right hand tray is in normal position, while the left is 105 in position to receive a stretcher, the links

then resting on blocks 32. The tray 33 is maintained in elevated position by a hook 34 which engages a pin 35 projecting from the tie bar. To convert the tray into a back it is only necessary to swing it up on edge as in Fig. 3, which brings the upholstered side into position for use.

The lower trays, 40, rest upon T bars 41 which are arranged to slide in guides 42 secured to the floor and are kept in place on the bars by plates 43 on the ends of the trays confined between pins 44 projecting from the sides of the bars.

The trays, which are all alike, are made with angle iron frames 50 having sheet metal bottoms 51, below which is the upholstery 52. At each side of a tray there are sockets 53 to receive the legs 54 of a stretcher. The lower trays are provided with the plates 43 before mentioned, and folding legs 55. In Fig. 3 the tray is standing on the legs. The sockets 53 serve the double purpose of keeping the stretcher in place on the tray and of holding the canvas bed taut, thereby dispensing with mechanism usually attached to the stretcher for this latter purpose, which interferes with folding the stretcher when not in use.

I do not wish to be understood to limit my invention to the embodiment herein shown as it is obvious that numerous deviations therefrom are possible. For example, it is not necessary to provide supports on both sides of the body. Again, either the sliding or the rocking form of support may be used alone, and the latter form in particular is susceptible of modification to meet particular requirements. By suitable changes in the position of the stops 32 the support 33 may when projected occupy a position below the level of the wheel top. If in doing this the upper end of link 28 approaches so close to link 27 that there is a tendency for the inner edge of the tray to drop down the links may be connected by toothed sectors and an intermediate gear, as indicated in dotted lines in Fig. 3. In Fig. 2 the links are connected by dotted lines S, representing tension springs by which the weight of the tray and links may be counterbalanced. As the manner of applying these additions would be readily understood by a mechanic, further illustration is deemed unnecessary.

55 What I claim is as follows:

1. An ambulance having a tray mounted upon bars which slide in or out of the body, said tray being adapted to carry a stretcher, and having legs whereon it may stand to form a seat.

2. An ambulance having a tray mounted upon bars which slide into or out of the ambulance body, said tray being adapted to carry a stretcher and having legs whereon it may stand to form a seat; and another

tray carried by links and thereby enabled to move into or out of the body and carry a stretcher, said tray being so attached to the links as to enable it to be rocked from its stretcher carrying position to a position 70 suitable for a seat back.

3. An ambulance having a pair of links attached to the body thereof, a tie bar connecting said links, a tray, one side of which is adapted to serve as a support for a 75 stretcher, the opposite side being adapted to serve as a back for a seat; means, including a pivot, whereby the tray is attached to and supported by the tie bar, said means maintaining the tray in a horizontal 80 position, ready to receive a stretcher, but permitting it to be rocked on said pivot to a position where its opposite side may be used as a seat back.

4. An ambulance having two stretcher 85 supports, one above the other, each adapted to be projected therefrom and carry a stretcher in or out while the other is occupied by a patient, means for maintaining the supports in horizontal position while 90 they are moving in and out, and means whereby each support is brought to the same level when projected.

5. An ambulance having two stretcher supports, each adapted to be projected therefrom and carry a stretcher in or out; and means for converting one of the supports into a seat and the other into a back for said seat.

6. An ambulance having a stretcher support arranged to slide in or out of the ambulance, moving transversely with reference to the stretcher it carries, and having another stretcher support carried on parallel links, one end of each link being pivotally attached to the support, the other end being pivoted to the ambulance body in such position that when in the ambulance the support is above the sliding support, and when moved out of the ambulance assumes a position at the height of the sliding support.

7. An ambulance having a stretcher support arranged to slide transversely with reference to the stretcher it supports and carry it in or out of the ambulance, and having another stretcher support carried on parallel links, one end of each link being pivotally attached to the ambulance body and the other end attached to the support, arranged so that by rocking the links the support may be moved into or out of the ambulance, this support and the stretcher carried by it occupying a position when in the ambulance sufficiently above the sliding support to afford access to the lower patient.

8. An ambulance having a stretcher support carried on two pairs of parallel links, one end of each link being pivotally attached to the ambulance body and the other

end attached to the support, arranged so that by rocking the links the support may be moved into or out of the ambulance, with or without a stretcher thereon; and a cross connection between a link of one pair and a link of the other pair, whereby both pairs of links are compelled to act in unison.

9. An ambulance having a stretcher support, each end of which is carried by a pair of parallel links which when the support is in normal position are approximately vertical, said links being pivotally attached at the top to the support and at the bottom to the body of the ambulance, so that when they rock on their lower pivots the support is lowered and projected from the body of the ambulance, two of the links being connected

by a shaft so that both ends of the support are compelled to move in unison.

10. An ambulance having a stretcher support, each end of which is carried by a pair of parallel links which when the support is in normal position extend upward, said links being pivotally attached at the top to the support and at the bottom to the body of the ambulance, so that when they rock on their lower pivots the support is projected from the body of the ambulance, two of the links being connected by a shaft so that both ends of the support are compelled to move in unison, said shaft being at a different level from the lower pivots of the other links.

CHARLES C. BLACKMORE.
